UNITED STATES PATENT OFFICE.

DAVID BAUM, OF LIVERMORE FALLS, MAINE.

GLOVE-TURNING MACHINE.

1,348,077.

Specification of Letters Patent. Patented July 27, 1920.

Application filed September 6, 1919. Serial No. 322,127.

To all whom it may concern:

Be it known that I, DAVID BAUM, a citizen of the United States, and a resident of Livermore Falls, in the county of Androscoggin and State of Maine, have invented a new and Improved Glove-Turning Machine, of which the following is a full, clear, and exact description.

This invention relates to improvements in glove turning machines, an object of the invention being to provide improved means for quickly turning a glove right-side-out or wrong-side-out as the case may be, and which operation is entirely automatic.

15 Gloves, and particularly cheap gloves of cotton, canvas and similar woven material, are made wrong-side-out and must be turned right-side-out before forwarding to the trade. It is the purpose of my invention to provide a machine, which at each complete operation, quickly and efficiently performs the function of reversing the glove; that is to say, turning it right-side-out ready for the trade.

20 A further object is to provide improved means for supporting the glove and improved means for causing the glove to be reversed.

25 A further object is to provide an improved arrangement of finger and thumb supports which receive the fingers and thumb of the glove and which hold the glove in position and assist in the reversing operation.

30 A further object is to provide an improved arrangement of thumb support which can be shifted from one position to another to accommodate both right and left gloves.

35 A further object is to provide improved means for gripping the glove and turning it while the fingers are being held and provide means for controlling all of the operations of the machine so that each operation will be timed and function in proper order.

40 With these and other objects in view the invention consists in certain novel features of construction, and combinations and arrangements of parts, as will be more fully hereinafter described and pointed out in the claims.

In the accompanying drawings—

45 Figure 1 is a view in side elevation illustrating my improvements;

Fig. 2 is a view in front elevation;

Figs. 3, 4, 5, 6 and 7 are views on an enlarged scale showing the different positions of parts during the operation of turning or reversing a glove;

60

Fig. 8 is a view in section on the line 8—8 of Fig. 5;

Fig. 9 is a view in section on the line 9—9 of Fig. 3;

Fig. 10 is a view in section on the line 10—10 of Fig. 9;

Fig. 11 is an enlarged fragmentary view in front elevation;

Fig. 12 is a detail view in front elevation of one of the pairs of gripping levers;

70

Fig. 13 is a view in longitudinal section of a modified form of finger support; and

Fig. 14 is an end view of Fig. 13.

1 represents a standard having a supporting bracket 2 fixed thereon and a vertically movable bracket 3. A drive shaft 4 is mounted in suitable bearings 5 at the upper end of standard 1 and has a drive pulley 6 connected thereto by means of a single revolution clutch 7, the latter operated by a rod 8 in the ordinary way to permit a single revolution of the shaft and a complete operation of the machine, which will be more fully hereinafter described.

25 A crank arm 9 is provided on the shaft 4 and is connected by a link 10 with the bracket 3 so that the bracket is given a complete downward and upward movement at each revolution of the shaft.

30 The bracket 3 has a dove-tailed recess 11 in its inner end receiving a dove-tailed guide plate 12 on the standard 1 and a strip 13 is interposed between the edge of plate 12 and the wall of recess 11 to insure a perfect engagement and to take up wear.

35 A bed plate 14 is secured on bracket 2 and is provided with screw threaded openings 15 to receive finger tubes 16, 17, 18 and 19 which are screwed into the openings 15, as indicated clearly in Fig. 10. I call these 40 parts 16, 17, 18 and 19 finger tubes because they are adapted to receive the fingers 20 of a glove 21 thereon, and, hence, these parts constitute finger tubes or supports to hold the fingers of the glove during the 45 turning operation.

50 A link 22 has rotary mounting on the tube 16 and supports a thumb tube 23. A pinion 24 is made integral with the link 22 and is mounted to turn freely around the 55

110

tube 16. This pinion 24 is in mesh with a gear wheel 25, the latter mounted on a post 26 secured to the bed plate 14 and bracket 2 by means of a screw 27. A housing 28 covers the gear wheel 25 and a forked strip 29 is located under the housing and projects into an annular groove 30 in the link 22 above pinion 24 to prevent vertical movement of the link and the thumb tube 23 carried thereby.

A pinion 31 is fixed to turn with gear wheel 25 and is operated by means of a rack bar 32, the latter mounted to move in a recess 33 in bed plate 14. A lever 34 is pivotally supported between its ends on the bracket 2, as shown at 35, and the upper end of the lever 34 is pivotally connected to the rack bar 32 by means of a pin 36. An enlargement 37 is provided on the lower end of the lever 34 and is adapted to be engaged by the knee of the operator to swing the thumb tube from one extreme position to another so as to accommodate right and left gloves, as will be understood.

The vertically movable bracket 3 supports six plungers 38, 39, 40, 41, 42 and 43 respectively. The plungers 38, 39, 40 and 41 are adapted to enter the finger tubes 16, 17, 18 and 19 while the plungers 42 and 43 are adapted to enter the thumb tube 23.

These plungers are positioned in bosses 44 on the bracket 3 and are secured by means of nuts 45, as clearly shown.

A pair of guide sleeves 46 and 47 are secured in bosses 48 on bracket 3 and have forked lower ends 49 carrying pivot pins 50. These pivot pins 50 are projected through the intermediate portions of crossed gripping levers 60 and 61 respectively.

Vertically movable rods 52 are mounted to move in the sleeves 46 and are made with toothed racks 53 at their upper ends and mesh with pinions 54. Cross heads 55 are provided on the lower ends of the rods 52, and links 56 and 57 respectively connect the ends of the heads 55 with the gripping levers 61 and 60 respectively. The links 57 have slot and pin connections 51 with the gripping levers 61 to permit of a certain amount of lost motion for a purpose which will hereinafter appear.

The levers 60 have recessed ends 58 to conform in shape to the glove around the tubes and the levers 61 have toothed ends 59 to grip the glove during the turning operation. The pinions 54 operating the racks 53 are fixed to turn with pinions 62 on shafts 63 and are supported in proper position by spacing sleeves 64.

A rack bar 65 is mounted to slide on the bracket 3 and is in mesh with both of the pinions 62. A coiled spring 66 is connected at one end to a pin 67 on the rack bar 65 and at its other end to a pin 68 on the bracket 3,

thus exerting a continuous inward pressure 65 on the rack bar.

A bracket 69 is connected by a pivot pin 70 with the inner end of rack bar 65 and weak springs 71 are located around the pins 70 and exert a pressure on the bracket 69 70 tending to hold the bracket in alinement with the rack bar 65. A roller 72 is carried by the bracket 69 and engages a cam strip 73 fixed to the plate 12 and having a beveled lower end 74 located in a recess 75 in the 75 said plate 12.

Any desired number of finger tubes may be provided with grippers 76 and 77, which are located inside of the tubes and pivotally supported between their ends, as shown at 80 78. These grippers have teeth 79 on their inner faces at their upper ends and their lower ends are pressed apart by springs 80 which tend to force the teeth 79 toward each other to grip the inwardly forced glove finger, as will be understood. The teeth 79 are beveled so as to permit the ready inward movement of the finger by means of the plunger and serve to grip the finger when the plunger is withdrawn.

The tubes are provided with slots 81 to accommodate the movement of the grippers. In the modification illustrated in Figs. 13 and 14 a plurality of spring grippers 82 constitute the upper end of the finger tube 83 and said grippers have a sufficient inward pressure at their upper ends 84 to grip the glove finger when it is turned inwardly.

A glove ejector 85, which constitutes a wire or rod, is supported on a fixed rod 86 100 extending outwardly from the standard 1 and a spring 87 engages the ejector and tends to force the lower free end thereof forwardly. During the greater portion of movement of the bracket 3, however, the plunger is held in a rearward position by reason of the cam action of a shoulder 88 on the bracket, but when the bracket reaches its highest position the ejector can move forwardly and throw the glove outwardly, as 110 will be explained.

The operation of my improved machine is as follows: Fig. 1 shows the position of the glove 21 on the finger and thumb supporting tubes and this operation of placing the glove is done by hand. As the bracket 3 moves downwardly, the plungers 38, 39, 40 and 41 will enter the finger tubes 16, 17, 18 and 19 and in doing so will press the fingers 20 of the glove 21 into the tubes. At the 120 same time, of course, the plunger 42 forces the thumb of the glove into the thumb tube 23. During this downward movement of the bracket 3 the grippers 60 and 61 are in an inoperative position because the bracket 125 69 on the end of rack bar 65 is positioned at an upward angle by reason of the engagement of the roller 72 with the straight edge

of the strip 73. This first or initial position of the parts is illustrated in Fig. 3.

The next position of the parts is indicated in Fig. 4, in which it will be noted that the 5 bracket 3 has moved downwardly far enough to allow the pivoted bracket 69 to move into the recess 75 and hence, the springs 71 have forced the bracket 69 into a position in alignment with the rack bar 65. This is the extreme lower position of the upper bracket. 10 As the bracket then moves upwardly to the position shown in Fig. 5, it will be noted that the rack bar 65 has been caused to move to the right of the figure by reason of the roller 72 which is against the edge of strip 15 73 and has mounted to this position along the beveled edge 74. This movement of the rack bar 65 brings the gripping levers 60 and 61 into operation causing their free ends 20 to grip the wrist portion of the glove, as clearly shown in Fig. 5.

It will also be noted in this figure that the grippers 76 and 77 are gripping the inwardly projecting portions of certain of the 25 glove fingers and, as above stated, I may employ any desired number of these internal grippers, but have found that the provision of two pairs of these grippers will perform good results.

30 Fig. 6 illustrates a further upward position of the bracket 3 in which it will be seen that the glove has been completely turned and the fingers thereof are being drawn out of the finger tubes. The gripping levers 60 and 61 will hold the glove and continue to hold the same until the glove fingers are free from the tubes and until the bracket 3 comes to a rest after the crank arm 9 has passed slightly over 35 its center and caused a slight downward movement of the bracket 3. This slight downward movement of the bracket 3 gives an upward tilting movement to the bracket 69 when the spring 66 completes this movement to the position shown in Fig. 7 and causes the gripping levers 60 and 61 to release the glove, as shown clearly in Fig. 7. At this time the ejector 85 swings forwardly and throws the glove out of the way.

40 A slot and pin connection 51 between link 57 and lever 61 permits a certain amount of lost motion so that the lever 60 comes into operation or position before the lever 61 begins to move. Hence, the lever 60 engages under the wrist portion of the glove and slightly wrinkles the same before the end of lever 61 moves downwardly to grip the material, thus insuring a tight gripping action to cause the turning of the glove when the grippers move upwardly and to overcome the holding action of the internal grippers in the tubes to pull the glove free from the same after the turning operation is complete.

When it is desired to shift the thumb tube so as to operate on right or left hand gloves, as the case may be, it is simply necessary to swing the lever 34. This operation can be readily performed by the leg or knee of the operator.

Various slight changes may be made in the general form and arrangement of parts described without departing from the invention, and hence I do not limit myself to the precise details set forth but consider myself at liberty to make such changes and alterations as fairly fall within the spirit and scope of the appended claims.

I claim:

1. A machine of the character stated, comprising a glove support, a movable member, plungers on the movable member adapted to engage the fingers of the glove and force them into the glove support, means for holding the inwardly turned fingers in the glove support, and gripping means on said movable member adapted to grip the wrist portion of the glove and move the same vertically while the finger portions of the glove are thus held.

2. A glove turning machine, comprising a glove supporting means, plungers movable into the glove supporting means to project the fingers of the glove therein, means for gripping the inwardly projecting glove fingers in the glove supporting means, means for gripping the wrist portion of the glove outside of the supporting means, and means for moving the last-mentioned gripping means while the first-mentioned gripping means holds the inwardly projecting fingers, whereby the glove is turned.

3. A glove turning machine, comprising a glove supporting means consisting of a plurality of glove finger supporting tubes, plungers movable into the tubes to project the fingers of the glove therein, finger gripping means in the tubes, means for gripping the wrist portion of the glove outside of the supporting means, and means for moving the last-mentioned gripping means while the first-mentioned gripping means holds the inwardly projecting fingers, whereby the glove is turned.

4. A glove turning machine, comprising a glove supporting means consisting of a plurality of glove finger supporting tubes varying in height in accordance with the length of the fingers, means for projecting the glove fingers into the tubes, independent means for holding the glove fingers in the tubes, and means for moving the wrist portion of the glove while the fingers thereof are held, whereby the glove is turned.

5. A glove turning machine, comprising a glove supporting means consisting of glove

5 finger supporting tubes, and a glove thumb supporting tube, means for moving the thumb tube to either side of the series of finger tubes, means for projecting the thumb and fingers of a glove into the thumb and finger tubes, means for holding the glove thumb and fingers in the tubes, and means for moving the wrist portion of the glove while the finger portions are held, whereby

10 the glove is turned.

6. A glove turning machine, comprising a glove supporting means consisting of a series of glove finger supporting tubes, a link pivotally connected to one tube, a glove thumb receiving tube supported on the link, 15 a pinion on the link, a gear meshing with the pinion, a pinion secured to the last-mentioned gear, a rack engaging the last-mentioned pinion, a lever adapted to move 20 the rack and shift the thumb tube to their side of the series of finger tubes, means for projecting the fingers and thumb of a glove into said tubes, means for holding the parts in this position, and means for 25 drawing the wrist portion of the glove off of the supporting means while the fingers are held.

7. A glove turning machine, comprising a glove supporting means, plungers movable into the glove supporting means to project the fingers of the glove therein, means for gripping the glove fingers in the supporting means, two pairs of gripping levers adapted to engage the wrist portion 30 of the glove, and means for moving the gripping levers and the glove while the fingers are held in the support in a direction to turn the glove.

8. A glove turning machine, comprising 40 a glove supporting means, plungers movable into the glove supporting means to project the fingers of the glove therein, means for gripping the glove fingers in the supporting means, two pairs of gripping jaws, 45 means for operating the jaws to grip the wrist portion of the glove, and means for moving the gripping jaws in a direction to withdraw the glove from the support while the fingers thereof are held, whereby the 50 glove is turned.

9. A glove turning machine, comprising a glove supporting means, plungers movable into the glove supporting means to project the fingers of the glove therein, means for gripping the glove fingers in the supporting means, a movable member, two pairs of gripping jaws supported by the movable member, and means operating the jaws to grip the wrist portion of the glove.

60 10. A glove turning machine, comprising a glove supporting means, plungers movable into the glove supporting means to project the fingers of the glove therein, means for gripping the glove fingers in the supporting means, a movable member, two

75 pairs of gripping jaws pivotally connected to said member, rods mounted to move in the member, heads on the rods, links connecting the heads with the gripping jaws, racks on the rods, pinions meshing with the racks, and means for operating the pinions to operate the gripping jaws, said gripping jaws adapted to engage the wrist portion of a glove and move the same while the fingers are held.

11. A glove turning machine, comprising a glove supporting means, plungers movable into the glove supporting means to project the fingers of the glove therein, means for gripping the glove fingers in the supporting means, a movable support, a cam strip on the movable support, two pairs of gripping jaws on the movable support adapted to engage the wrist portion of a glove, a movable member controlling the operation of the gripping jaws, a pivoted bracket on the movable member engaging the cam strip, and said pivoted bracket operated to release the glove from the grippers when the movable member reaches a predetermined position.

12. A machine of the character stated, comprising a glove support, a movable member, plungers on the movable member adapted to engage the fingers of the glove and force them into the glove support, means for holding the inwardly turned fingers in the glove support, gripping means on said movable member adapted to grip the wrist portion of the glove and move the same vertically while the finger portions of the glove are thus held, an ejector, and means controlling the operation of the ejector to engage the glove and force it laterally when released by the glove grippers.

105 13. A glove turning machine, comprising a glove supporting means, plungers movable into the glove supporting means to project the fingers of the glove therein, means for gripping the inwardly projecting glove fingers in the glove supporting means, means for gripping the wrist portion of the glove outside of the supporting means, means for moving the last-mentioned gripping means while the first-mentioned gripping means hold the inwardly projecting fingers, whereby the glove is turned, an ejector, and means controlling the operation of the ejector to engage the glove and force it laterally when released by the glove grippers.

115 14. A glove turning machine, comprising a glove supporting means consisting of a plurality of glove finger supporting tubes, plungers movable into the tubes to project the fingers of the glove therein, finger gripping means in the tubes, means for gripping the wrist portion of the glove outside of the supporting means, means for moving the last-mentioned gripping means while the 120

130

- first-mentioned gripping means holds the inwardly projecting fingers, whereby the glove is turned, an ejector, and means controlling the operation of the ejector to engage the glove and force it laterally when released by the glove grippers.
15. A glove turning machine, comprising a glove supporting means consisting of a plurality of glove finger supporting tubes 10 varying in height in accordance with the length of the fingers, means for projecting the glove fingers into the tubes, independent means for holding the glove fingers in the tubes, means for moving the wrist portion 15 of the glove while the fingers thereof are held, whereby the glove is turned, an ejector, and means controlling the operation of the ejector to engage the glove and force it laterally when lifted off the said tubes.
20. 16. A glove turning machine, comprising a glove supporting means consisting of glove finger supporting tubes, and a glove thumb supporting tube, means for moving the thumb tube to either side of the series

of finger tubes, means for projecting the 25 thumb and fingers of a glove into the thumb and finger tubes, independent means for holding the glove thumb and fingers in the tubes, means for moving the wrist portion of the glove while the finger portions are held, whereby the glove is turned, an ejector, and means controlling the operation of the ejector to engage the glove and force it laterally when lifted off the said tubes.

17. A glove turning machine, comprising 35 a standard, a fixed bracket on the standard, glove supporting means on the fixed bracket, a movable bracket mounted on the standard, plungers on the movable bracket adapted to force the fingers of the glove into the glove 40 support, grippers on the movable bracket adapted to engage the wrist portion of the glove, means on the standard controlling the operation of said grippers, and gripping means in the glove support for holding the 45 fingers when they are projected inwardly by the plunger.

DAVID BAUM.
